UTILITY BAG

Max Freedland, New York, N. Y., assignor to
Empire Shield Co., Inc., a corporation of New
York

Application September 17, 1942, Serial No. 458,680

2 Claims. (Cl. 190—48)

This invention relates to new and useful improvements in a utility bag.

More specifically, the invention proposes the construction of a bag-like body having a bottom wall and side walls with large radii top corners and relatively low end walls with flexible extensions projected inwards from the tops of the side walls and directed towards each other in a manner to close the open top of the bag.

A further object of the invention proposes the provision of flexible stiff reinforcement strips mounted along the overlapping edges of the flexible extensions in a manner to be bent to conform with the contour of the top edges of the side walls to retain the extensions in their overlapped positions in which they close the open top of the bag.

A still further object of the invention proposes the provision of a novel means arranged in connection with the ends of the flexible strips and engageable with the end walls of the bag in a manner to retain the flexible strips in their arched condition conforming with the top edges of the side walls.

Another object of the invention proposes the provision of a means arranged in connection with the topmost flexible extension for holding the center portions of the extensions overlapped against the outward force of the contents of the bag when overstuffed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a utility bag constructed in accordance with this invention.

Fig. 2 is a plan view of Fig. 1.

Fig. 3 is a perspective view of the utility bag in its open condition.

Fig. 4 is an end elevational view of the utility bag in its closed condition.

Fig. 5 is a partial vertical sectional view on the line 5—5 of Fig. 4.

Fig. 6 is a partial vertical sectional view on the line 6—6 of Fig. 5.

Fig. 7 is an end elevational view similar to Fig. 4 but illustrating a modification of the invention.

Fig. 8 is a perspective view of one end of the bag shown in Fig. 7.

The utility bag, according to this invention,

includes a bag-like body 10 having a bottom wall 11, side walls 12 and relatively low end walls 13. The bag 10 is constructed of duck, canvas, leather or other similar materials, and has its bottom wall reinforced to maintain a flat condition by means of a board 14. The side walls 12 have large radii top corners which extend from the top ends of the relatively low end walls 13 to the top edges of the side walls 12.

Handles 17 have their ends attached to the side walls 12 and provide a convenient means by which the bag 10 may be easily carried about.

Flexible extensions 18 extend from the top edges of the side walls 12 and are directed inwards and towards each other forming the top of the bag 10. The flexible extensions 18 have their inner edges overlapped and follow the contour of the top edges of the side walls and extend downwards and over the top edges of the end walls 13. Flexible and stiff reinforcement strips 19 are mounted along the overlapping edges of the flexible extensions 18. The reinforcement strips 19 are preferably formed of metal and are disposed within pockets 20 formed along the free edges of the flexible extensions 18. These pockets 20 are formed by bending the free edges of the extensions 18 under and outwards and securing the bent under portions in position by a line of stitches 21.

30 The reinforcement strips are adapted to be flexed to follow the contour of the top edges of the side walls 12 when overlapped to retain the flexible extensions 18 in their overlapped condition so as to close the open top of the bag 10.

35 Means is provided for retaining the reinforcement strips 19 in their flexed condition. This means is identical for both ends of the bag 10 and is characterized by a loop 22 mounted on one of the superimposed ends of the metal strips 19. A strap 23 is mounted on the other of the superimposed ends and is adapted to be engaged through its respective loop 22 and is formed with a plurality of openings 24 selectively engageable with a tongue 25 of a buckle 26 mounted on the

40 adjacent end wall 13 of the bag 10. The engagement of the straps 23 with the buckles 26 will maintain the reinforcement strips 19 in their flexed position and maintain the bag closed.

45 However, when the straps 23 are disengaged from the buckle 26 the reinforcement strips 19 will straighten out and permit the extensions 18 to be directed outwards to open the top of the bag 10.

50 Means is provided in connection with the topmost overlapped portion of the flexible exten-

sions 18 for assisting the straps and buckles in maintaining the extensions 18 closed against the outward force of the contents of the bag when overstuffed. This means comprises a strap 27 attached to the center of the topmost overlapped portion and engageable with a complementary buckle 28 mounted on the opposed side wall 12 of the utility bag 10. When the bag has been overstuffed the engagement of the strap 27 with the buckle 28 will pull the flexible extensions 18 together and prevent the center of these extensions from being opened under the outward force of the contents of the bag.

In the form of the invention disclosed in Figs. 7 and 8 the construction of the utility bag is similar to that previously described except for the provision of a slightly different means for attaching the free ends of the straps 23' in position with relation to the end walls 13 of the bag 10. In this form of the invention the straps 23' after being passed through the loops 22 are then passed into and out of adjacent slits 24' formed in the end walls 13. The free end of each strap 23' is provided with a snap fastener element 25' which is engageable with a complementary snap fastener element 26' mounted upon the bottom face of the bottom wall 11. Before the snap fastener elements 25' may be engaged with the snap fastener elements 26' it is necessary that the free ends of the straps 23' be bent around the bottom corners of the bag 10.

The corners of the bottom wall of the bag 10 are provided with small foot members 29 upon which the bag 10 may be rested so as to prevent the ends of the straps 23' from contacting the ground when set down.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A utility bag, comprising a bag-like body having a bottom wall, side walls with large radii top corners, and relatively low end walls, flexible extensions from the tops of said side walls directed towards each other forming the top of said bag and overlapping and following the contour of the top edges of said side walls and extending downwards and over the top edges of said end walls, flexible and stiff reinforcement strips mounted along the overlapping edges of said flexible extensions and flexed and following the curved contour of said flexible extensions, loops connected with the ends of one of said strips, straps connected with the ends of the other of said strips and passing through said loops and holding said strips in their flexed positions, and means for releasably connecting said straps to said body, whereby when said straps are released said strips will unflex and straighten and said bag will be open.

2. A utility bag, comprising a bag-like body having a bottom wall, side walls with large radii top corners, and relatively low end walls, flexible extensions from the tops of said side walls directed towards each other forming the top of said bag and overlapping and following the contour of the top edges of said side walls and extending downwards and over the top edges of said end walls, flexible and stiff reinforcement strips mounted along the overlapping edges of said flexible extensions and flexed and following the curved contour of said flexible extensions, loops connected with the ends of one of said strips, straps connected with the ends of the other of said strips and passing through said loops and holding said strips in their flexed positions, and means for releasably connecting said straps to said body, whereby when said straps are released said strips will unflex and straighten and said bag will be open, said straps being passed into and out of adjacent slits formed in the end walls of said bag-like body and said means comprising snap fastener elements on the free ends of said straps and engageable with complementary snap fastener elements on the bottom of said bag.

MAX FREEDLAND.
